UNITED STATES PATENT OFFICE

2,446,665

HUMIDIFIER

Joseph J. Rozner, Chicago, Ill.

Application January 15, 1944, Serial No. 518,426

4 Claims. (Cl. 261—25)

1

My invention relates to humidifiers.

The object and accomplishment of the invention is to provide a simple, sturdy device, capable of being economically manufactured and easily installed, that may be associated with a steam radiator for the purpose of disseminating water vapor by fan action.

A salient feature of the invention is that the fan is driven by a fluid actuated impeller operating in a suitable housing that intakes impeller-motivating steam from the radiator and exhausts water vapor into the ambit of the fan.

Other features, objects and advantages of my invention will appear from the following detailed description wherein reference is made to the accompanying sheet of drawings in which:

Figure 1 is an elevational view illustrating the humidifier of the present invention associated with one of the end risers of a conventional steam radiator;

Fig. 2 is a side view in which the impeller housing and parts within it are depicted in axial section; and

Fig. 3 is a sectional view taken in the vertical planes of the line 3—3 of Fig. 2 and looking in the direction indicated by the arrows.

Similar characters of reference refer to similar parts throughout the several views.

In the drawings reference numeral 4 indicates a conventional steam radiator having a tubular elbow 5 communicating with one of its end risers.

Supported by the upturned end of elbow 5 is a composite housing which comprises the metallic portion or housing proper 7 and the circular closure plate 8, conveniently of non-metallic material, which suitably is retained in position by the swaged annular lip 9 of portion 7.

Forming parts of the housing portion 7 are the aligned bosses 10 and 11 which are bored to receive a bearing 12 for a freely rotatable shaft 13.

Fixed upon the inner end of the shaft 13 is a steam actuated impeller or turbine 14 which consists of a disk 15 provided with a multiplicity of suitably disposed equi-distantly spaced integral blades 16. Disk 15 conveniently is provided with a hollow integral central boss 17 for the reception of and fixation to the enlarged end 18 of shaft 13. If desired, a washer 19 may encircle shaft 13 and be disposed between the opposed ends of bosses 10 and 17. Impeller 14 may be in the form of a metal stamping, a molded plastic, or be fabricated from a suitable material or materials. Apertures 20 may be formed in disk 15 for the sake of lightness, or to economize in the

2

use of the material from which the impeller is formed.

Fixed to the outer end of shaft 13 is a fan 21 which preferably, but not necessarily, is of the rubber blade variety having four blades.

Steam to rotate the impeller or turbine 14 is admitted to housing 6 through an intake port 22 which conveniently is controlled by a needle valve 23. The location of the intake port 22 is desirable at the bottom of the housing, so that moisture of condensation of the steam within the housing drains back to the port for return to the radiator or reprojection with the steam against the impeller for atomization.

Housing 6 is provided with one or a plurality of exhaust ports 24 disposed relatively close to the fan axis on the low pressure side of the fan and discharging toward the fan in a line normal to the plane of fan rotation. This relation of parts further promotes dispersion of the moisture of the steam into the air by utilizing the mechanical action of the fan to atomize condensed moisture and disperse all of the moisture into the air without providing any places for moisture to collect in condensed form and from which it will drip.

Steam admitted to the housing 6 through port 22 impinges upon the blades 16 to rotate the impeller 14 in the direction indicated by the arrows (Fig. 3), and the resultant water vapor which accumulates within housing 6 is exhausted in vaporized and atomized form through ports 24 into the ambit of fan 21, in the region of the fan axis, to be quite thoroughly disseminated by fan action throughout the room in which the humidifier is located.

By "ambit" of the fan, as the term is used herein, I mean its field of action.

Having thus illustrated and described a preferred embodiment of my invention, what I claim as new and desire to secure by Letters Patent of the United States is:

1. In a humidifier adapted to be operated by steam under pressure, the combination of a casing having an opening at one end, an inlet port 45 at the bottom, an exhaust port in the end opposite said opening in a position higher than said inlet port, a closure plate secured in said opening, a shaft journaled in said exhaust port end and adjacent said exhaust port, an impeller secured to said shaft within the casing, said impeller including a disc provided with a multiplicity of circumferentially disposed equi-distantly spaced integral blades, said impeller revolving in a plane parallel with the closure plate, said blades 50 being in position to intercept the steam entering

the casing through the inlet port so as to drive said impeller, said blades also serving to atomize the moisture of condensation within the casing, and a fan mounted on the shaft outside of said casing adjacent said exhaust port and in the path of steam issuing therefrom, said steam entering the ambit of said fan on the low pressure side thereof, said fan being driven by said impeller to disseminate the steam into the atmosphere, said fan by mechanical action atomizing condensate which forms after the steam escapes from the exhaust port.

2. In a humidifier adapted to be operated by steam under pressure, the combination of a casing having an opening at one end, an inlet port 15 at the bottom, an exhaust port in the end opposite said opening in a position higher than said inlet port, a closure plate secured in said opening, a shaft journaled in said end opposite the opening and adjacent said exhaust port, an impeller secured to said shaft within the casing, said impeller including a disc provided with a multiplicity of circumferentially disposed equi-distantly spaced integral blades, said impeller revolving in a plane parallel with the closure plate, said blades being in position to intercept the steam entering the casing through the inlet port so as to drive said impeller, said blades also serving to atomize the moisture of condensation within the casing, and a fan mounted on the shaft outside of said casing adjacent said exhaust port and in the path of steam issuing therefrom, said steam entering said fan on the low pressure side, said fan being driven by said impeller to disseminate the steam into the atmosphere, said fan by mechanical action atomizing condensate which forms after the steam escapes from the exhaust port, said inlet port also acting as a drain for any condensate which is not vaporized, said condensate in said inlet port being revaporized by the incoming steam and returned into the impeller blades to be exhausted through the exhaust port.

3. A humidifier adapted to be operated by steam under pressure from a source thereof and comprising, in combination, a housing having a steam inlet port at the bottom for connection to the source of steam under pressure and an exhaust port in one side, a shaft journaled in said one side of the housing near the exhaust port, an impeller secured to the shaft within the housing in position to intercept and be driven by steam

5 entering the housing through the inlet port and exhausted through the exhaust port, said impeller also serving to atomize moisture of condensation within the housing which drains back to the inlet port, and a fan mounted in an exposed position on the shaft outside of the housing adjacent and in the path of steam exhausted from the exhaust port, said fan being so constructed and disposed relative to the exhaust port that the steam exhausted through said exhaust port enters the ambit of the fan on the lower pressure side thereof, said fan being driven by the impeller to disperse the moisture of the steam.

4. In a humidifier adapted to be operated by steam under pressure from a source thereof, the combination comprising a housing providing an enclosure having a steam inlet port at the lowermost internal portion thereof for connection to the source of steam under pressure and an exhaust port at a higher position, an impeller having blades, and means rotatably supporting the impeller within the housing in alignment with the inlet port to be driven by steam entering the inlet port and passing to the exhaust port, the positions of said inlet and exhaust ports being such that moisture of condensation from the steam drains to the inlet port and is prevented from draining through the exhaust ports, a fan mounted outside of said housing adjacent said exhaust port and rotatably supported by the impeller supporting means to be driven thereby, said fan being so constructed with respect to the normal direction of rotation of the impeller supporting means and so disposed with respect to said exhaust port that steam issuing from the exhaust port enters the ambit of the fan on the low pressure side thereof.
